UNITED STATES PATENT OFFICE

EVERETT DANIEL, OF MOULTRIE, GEORGIA

CROSSING GATE

Application filed February 10, 1930. Serial No. 427,303.

This invention aims to provide a novel means whereby a gate will be closed at a railroad crossing, whilst a train is at some distance from the crossing, and be opened as the train clears the crossing.

It is within the province of the disclosure to improve generally and to enhance the utility of devices of that sort to which the invention appertains.

With the above and other objects in view, which will appear as the description proceeds, the invention resides in the combination and arrangement of parts and in the details of construction hereinafter described, and claimed, it being understood that changes may be made in the precise embodiment of the device herein disclosed, within the scope of what is claimed, without departing from the spirit of the invention.

In the drawings:

Figure 1 shows in plan a device constructed in accordance with the invention, parts being broken away;

Figure 2 is an elevation showing the gate raised, some parts being in section;

Figure 3 is an elevation showing the gate raised, parts being in section;

Figure 4 is a view of the structure shown in Figure 3, parts being sectioned at right angles to the showing of Figure 3;

Figure 5 is an elevation showing the gate closed, parts being in section;

Figure 6 is a view similar to Figure 3, but showing the parts as they will appear when the gate is closed;

Figure 7 is a view similar to Figure 4, but showing the parts as they will appear when the gate is closed;

Figure 8 is a cross section showing in elevation a portion of the mechanism whereby the gate is controlled;

Figure 9 is a plan showing one of the ramps;

Figure 10 is an enlarged section showing the guide, the latches, and attendant parts;

Figure 11 is an elevation of one rack bar;

Figure 12 is an elevation of the other rack bar.

Figure 13 is a plan showing a modification, parts being broken away;

Figure 14 is a longitudinal section of the structure depicted in Figure 13.

In the drawings, there is shown a railroad track comprising a rail 1, and a rail 2, supported on ties 3, 4, and 5, the ties 4 and 5 being somewhat longer than the rest of the ties. The numeral 6 designates a highway that crosses the railroad track. Ramps 7 and 8 are disposed on opposite sides of the highway 6 at a proper distance therefrom. The ramps 7 and 8 are disposed closely adjacent to the rail 1. The ramps 7 and 8 are mounted at 9 in such a way that they can swing both vertically and horizontally. The ramps 7 and 8 are raised by springs 10. The ramps 7 and 8 are swung in against the rail 1 by springs 11. The inner ends of the ramps 7 and 8 are beveled, as shown at 12.

When the ramps 7 and 8 are depressed, they cooperate with cranks 14 on the inner ends of shafts 15 mounted to rock on the ties 3. The shafts 15 have cranks 16 at their outer ends. The outer end of a bar 17 is pivoted to one of the cranks 16. The outer end of a bar 19 is pivoted to the other of the cranks 16. The bar 17 has an upwardly-facing rack 18. The bar 19 has a downwardly-facing rack 20. The bars 17 and 19 slide in a grooved guide 21 on the ties 4 and 5. The racks 18 and 20 mesh with opposite portions of a pinion 22. The pinion 22 is secured to a shaft 23. The shaft 23 can rock in bearings 24 on the tie 5.

There is a crank 25 at the outer end of the shaft 23. An inclined guide, in the form of a cylinder 26, is mounted on a bracket 27 secured to a post 28 erected on the tie 4. A slide is mounted to reciprocate in the guide or cylinder 26.

The slide includes a rod 29 and a head 30 located in the cylinder 26. There is a crutch 31 at the upper end of the rod 29. The crutch 31 is adapted to cooperate with a gate 47. The gate 47 is pivoted at 48 to the post 20 to swing vertically. Swinging movement of the gate 47 to an open position is limited by a stop 49 on the post 28, as shown in Figure 3.

When the gate 47 is lowered, as in Figure 6, it forms a barrier extended across the highway 6. A link 32 is pivoted to the lower end

100

of the rod 29 and to the crank 25 of the shaft 23. A strong compression spring 33 is disposed in the cylinder 26. The lower end of the spring 33 engages the cylinder 26, and the 5 upper end of the compression spring engages the head 30 of the rod 29.

Figure 10 shows that oppositely-disposed depending spring latches 34 are secured at their upper ends to the cylinder 26. On the 10 lower ends of the latches 34, there are projections 35. The projections 35 extend through holes 36 in the cylinder 26 into the path of the head 30 of the rod 29. A cross piece 37 is secured to the cylinder 26. The pulleys 38 are journaled on the cross piece 37. The branches 39 of a crotch line 40 are connected to the lower ends of the spring latches 34. The branches 39 are rove over the pulleys 38. The crotch line 40 is connected (Figure 6) to 20 a crank 41 (Figure 7) on a shaft 42 mounted to rock on the tie 4. On the inner end of the shaft 42 there is a crank 43. The crank 43 is engaged with a depending hanger 44 (Figures 2 and 8) on an upwardly-flexed wheel-actuated resilient member 45 extended lengthwise of the rail 1, in close relation with the rail 1. The wheel-actuated member 45 is connected at 46 by a pin-and-slot mechanism, or in any other suitable way, with the ties 3, 25 so that the member 45 can spring up and down.

If a train is going in the direction of the arrow A in Figure 1, the wheels of the train will run over the ramp 7 and depress it, rotation being imparted to the corresponding 35 shaft 15 by way of the crank 14, the crank 16 operating the rod 17, and rotation being imparted to the shaft 23 by way of the rack 18 and the pinion 22. When the shaft 23 is 40 rotated as aforesaid, it assumes the position of Figure 6, the crank 25 swinging down, and the link 32 pulling the rod 29 and the head 30 down, this operation permitting the gate 47 to close across the highway 6.

45 When the head 30 is pulled down into the position of Figures 6 and 10, it causes the spring latches 34 to carry the projections 35 inwardly on top of the head 30. The gate, thus, remains closed until the train runs on 50 the wheel-actuated member 45 and shoves it down. Then rotation is imparted to the shaft 42 of the crank 43 and the crank 44 of Figure 5, and the arm 41 on the shaft 42 pulls on the crotch line 40, the branches 39 of the 55 crotch line running over the pulleys 38 (Figure 10) of the cross piece 37, and pulling the projections 35 of the latches 34 out from above the head 30 of the rod 29. The spring 33 now reacts on the head 30 and shoves the rod 29 up into the position of Figure 3, the 60 crutch 31 raising the gate 47. The projections 35 are rounded so that when the head 30 moves downwardly, it can pass the projections 35, and engage beneath them, as 65 shown in Figure 10.

When the train, moving in the direction of the arrow A in Figure 1, gets to the ramp 8, it does not shove this ramp down and close the gate 47 again. This is so because the 70 flange of the car wheels can engage with the ends 12 of the ramp 8 and swing it horizontally without forcing it down. Figure 9 shows how this operation is carried out in connection with the ramp 7 when the train is moving in a direction opposite to that indicated by the arrow A in Figure 1.

In the form shown in Figures 13 and 14, parts hereinbefore described have been designated by numerals previously used, with the suffix "a".

The modification resides in a change in the train-operated means for retracting the slide 29—30 of Figure 3 to close the gate, the racks 18—20, and the pinion 22 of Figure 2 being replaced by a structure now to be described.

On the inner end of the shaft 23a there is an arm 50 having transversely extended fingers 51 provided with elongated slots 52 in which anchors 53 (such as eye bolts) are adjustably clamped. The outer ends of flexible elements 54 are connected to the cranks 16a, the inner ends of the flexible elements being connected to the anchors 53. The flexible elements 54 extend in opposite directions around pulleys 56, supported for rotation on the cross ties, or elsewhere. One flexible element may be carried under the highway 6a through a tubular guide 55, and the other flexible element can slide through fair-leaders 57 on the cross ties.

As to the form shown in Figures 13 and 14, this specification need not be encumbered by tracing out the whole operation again. It is enough to state that in the retraction of the slide 28—30 of Figure 3, motion is derived from the train-operated means (comprising the cranks 16a of Figure 3) through the flexible elements 54 and the arm 50 on the shaft 23a, it being possible to shift the anchors 53, in the slots 52 of the fingers 51 in the arms 50, so that there will be no undesirable amount of slack in the flexible elements 54.

What is claimed is:

1. In a device of the class described, a track rail, a ramp, means for mounting the ramp at one end for swinging movement both vertically and horizontally, spring means for raising the ramp whereby a car wheel going in one direction will depress it, spring means for swinging the ramp horizontally against the rail, the ramp being beveled on its opposite end whereby a car wheel going in an opposite direction will swing it horizontally without depressing it, a gate mounted for vertical swinging movement, a slide sustaining the gate in open position when the slide is advanced, and means for connecting the slide with the ramp, whereby when the ramp is depressed, it will retract the slide as the gate closes.

2. The combination with a vertically swinging gate, so pivoted as to close by gravity, of a slide having a crutch in which the gate rests detachably, means for mounting the slide for reciprocation, spring means engaged directly with the slide to advance the slide and open the gate, train operated means for retracting the slide, thereby permitting the gate to close by gravity and slide 5 in the crutch as it closes, latch mechanism cooperating with the slide to hold the slide retracted when the gate is closed, and train operated means for releasing the latch mechanism from the slide, thereby rendering the 10 15 spring means active to open the gate.

3. The combination with a vertically swinging gate, of a slide having a crutch in which the lower edge of the gate is slidably received, means for mounting the slide 20 for right line movement, the slide and said means being disposed at an acute angle to the gate when the gate is horizontal and at an obtuse angle to the gate when the gate is opened, whereby the gate can have longitudinal 25 sliding movement relative to the crutch when the gate is being opened and when the gate is being closed, spring means coacting with the slide to advance it and open the gate, train operated means for retracting the slide, to permit the gate to close, latch mechanism cooperating with the slide, to hold the slide retracted when the gate is closed, and train operated means for releasing the latch mechanism from the slide thereby to render the spring means active to open 30 35 the gate.

4. In a device of the class described, a vertically swinging gate, a side on which the gate rests removably, and on which the gate moves longitudinally as the gate opens and closes, means for mounting the slide for right line reciprocation, spring means cooperating 40 with the slide to advance the slide and open the gate, train operated means for retracting the slide thereby to permit the gate to close, latch mechanism cooperating with the slide to hold the slide retracted when the gate is closed, and train operated means for releasing the latch mechanism from the slide, thereby to render the spring means active to open 45 50 55 the gate.

In testimony that I claim the foregoing as my own, I have hereto affixed my signature.

EVERETT DANIEL.
